UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed December 24, 1920. Serial No. 432,906.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to collating and feeding means for typewriters.

More particularly, it relates to billing machines, in which are typed, at one time, several sheets, such as a work-sheet or tally-strip, bill-sheet, and ledger-sheet, said bill and ledger sheets being separately gaged laterally (because of their varying widths) and also longitudinally, to permit entries that are made at intervals to be accurately aligned and spaced one under another upon the bill, ledger and record sheets.

The present invention is generally similar in purpose to the invention disclosed in my application No. 404,882, filed August 20, 1920 (now Patent No. 1,487,671, of March 25, 1924). A wide ledger-sheet may be gaged by passing it down over a rear paper-table, provided with side-edge gages, and bringing it up in front of the platen, so that its upper end lies upon a front paper-table, provided with side members, against which the ledger-sheet is gaged laterally. Two sets of auxiliary and co-operating feed-rolls or collating-rolls are provided at the front table, said ledger-sheet being clamped between said collating-rolls by the actuation of a finger-piece after being adjusted laterally on the front paper-table. These collating-rolls lie outside of the margins of the narrower bill-sheet, upon which most of the original entries are made. The bill-sheet is then passed down and gaged laterally by a chute which may be formed in the rear paper-table, to carry the narrower sheet clear of the first inserted sheet, and guided upwardly between side gages provided upon an auxiliary front paper-table which stands clear of the main front paper-table, for the wider sheet, but which is fixed to the side members of said main front table.

A record-sheet may be fed around the platen to the rear of the ledger-sheet and the auxiliary rolls, and beneath the front tables. The record-sheet may be a

tally-strip, and may be held in position on the platen by a suitable tally-strip device.

The auxiliary front paper-table, adjacent one of the side gages for the bill-sheet, is provided with a sheet-gripping clamp which can be operated to hold said sheet in adjusted position while the work-sheet or ledger-sheet is adjusted, by means of the collating rolls.

The shaft of one set of auxiliary feed-rolls is provided with a finger adapted to rest adjacent the flat surface of the auxiliary front paper-table, said finger lying beneath said clamp, so that, when the auxiliary rolls are cast off to release the ledger-sheet, the clamp will also be rendered ineffective in order to release the bill-sheet.

When all the sheets have been adjusted laterally and longitudinally with respect to each other, the usual pressure-roll release-handle is operated to clamp all the work-sheets against the platen, preferably before the collating-rolls and the clamp have been released. While the usual feed-rolls are released, and while the ledger-sheet and the bill-sheet are held, respectively, by the collating-rolls and by the clamp, if desired, yet another work-sheet may be inserted and gaged, as an outer sheet. There may be provided an upwardly-extending finger pivotally attached to the frame of the carriage and adapted to rest at the front of the auxiliary front collating-table to engage the sheets at a point intermediate their side edges. There may be provided also an additional wing-scale to aid in aligning sheets inserted into the machine when the platen is near one end of its travel before being brought back for the beginning of a new line of typing.

Other features and advantages will hereinafter appear.

In the accompanying drawings,

Figure 1 is a perspective view of an Underwood machine, with the invention applied thereto, only such parts of the machine as co-operate with the invention being shown.

Figure 2 is a top view of the front collating-tables and the side gages attached thereto.

Figure 3 is a detail showing a suitable mounting for the sheet-collating rolls.

Figure 4 is a vertical section of the device shown in Figure 1, the collating-rolls and the clamp on the auxiliary collating-table being shown in full lines in their effective 5 positions and in broken lines in their ineffective positions.

A bill-sheet 10 and a ledger-sheet 11 are adapted to be passed downwardly over a rear paper-table 13, around the platen 15, 10 mounted upon axle 16, journaled in the end walls 17 of the platen-frame of the usual carriage. A record-sheet, which is here shown as a tally-strip 12, is fed from feed-roll 20 of a tally-strip device 21, mounted 15 on the end walls 17 of the carriage, said strip passing around the platen to a winding roll 22.

The ledger-sheet 11 is fed over the rear paper-table between adjustable side gages 20 25, movable along rod 26, fixed on brackets on the rear of the paper-table. The narrower bill-sheet is adapted to be fed over the paper-table in a depression or chute 30, forming side-edge gages therefor, said chute 25 merging with the extension 31 of the paper-table, forming the usual paper-apron. Front and rear pressure-rolls or feed-rolls 32 and 33 are adapted to press the sheets against the platen.

Passing around the platen, the ledger and bill-sheets are carried upwardly in front of the platen, where the ledger-sheet 11 is adapted to be adjusted upon a front collating-table 35. It is understood that until all 35 the work-sheets are adjusted relatively to each other, the pressure-rolls 32 and 33 remain cast off the platen.

As shown in Figure 1, the collating-table 35 is composed of two sections carried by 40 supports 36 suitably mounted on the end plates 17 of the carriage-frame. The collating-table 35 is provided with side edge gages 37 which co-operate with the side edge gages 25 to guide the ledger-sheet 11 at the 45 front and rear. The collating-table is also provided with openings 40, into which project collating-rollers 41 from the rear, and co-operating with said rollers are collating-rollers 42 at the front of the collating-table. Rollers 41 and 42 are mounted upon 50 shafts 43 and 44, respectively, shaft 43 being journaled in the end walls of the carriage and having a knob 45 at its outer end for turning said shaft, in order thereby to adjust 55 the ledger-sheet 11 relatively to the printing line on the platen. Shaft 44 and rollers 42 may be swung forwardly to move the rollers 42 out of contact with rollers 41, because said shaft is fixed to rock-arms 46, 60 which are fixed to short shafts 47, journaled in brackets 50 on each end wall 17. Shaft 44 has an extension 51, upon which is fixed a finger-piece 52. By swinging finger-piece 52 forwardly, rollers 42 are swung away 65 from rollers 41, and by swinging said

finger-piece rearwardly, rollers 42 are brought into gripping relation with rollers 41. The shafts 47, journaled in brackets 50, normally tend to press feed-rollers 42 rearwardly, because said shafts are each provided with a cam having a depression in each of which normally seats a projection on a spring-pressed follower 53, pivoted at 54 on each bracket. When the pressure-rollers 32 and 33 are cast off and the collating-rolls 41 and 42 are in engaging relation, 70 rotation of knob 45 will feed a sheet upwardly, or downwardly, to any desired extent. In this way the sheet gripped by the collating-rolls 41 and 42 may be adjusted to 75 any desired position relatively to the printing line on the platen.

The ledger-sheet, being gaged and guided by said edge gages 25 and 37, passes between rollers 41 and 42, which are rotated by 80 means of knob 45 to properly position the ledger-sheet longitudinally. Bill-sheet 10 is passed around the platen outside the ledger-sheet by passing it into the depression or chute 30. The bill-sheet is guided by extension 31 to the front of the platen and is led in front of the ledger-sheet 11 to an auxiliary table 56, carrying auxiliary side edge gages 57 thereon, and shown as formed in 85 two sections. The table 56, as shown in Figures 1 and 2, has downturned flanges 58, which are fixed to the side gages 37 of the main collating-table. There is thus provided a space 60 between the main and auxiliary collating-tables, through which passes 90 the ledger-sheet. The bill-sheet passes over the auxiliary collating-table 56 and is gaged at the front by side edge gages 57, and at the rear by the side walls of chute 30.

While pressure-rolls 32 and 33 are cast off, the ledger-sheet is held in position by rollers 41 and 42. The bill-sheet is held by a clamp pivoted on one of the sections of the collating-table 56 and adapted to be 105 swung over a side gage 57 against the bill-sheet. The clamp consists of a member 61, pivoted at 62 to a bracket 63, fixed to the table 56. The member 61 has a bent portion 64 adapted to avoid contact with the side gage 57, and has a rubber band 65 at 110 its end adapted to press the bill-sheet against table 56. A spring 66 is fixed to the bracket 63 and a pin 67 on member 61 in such manner as to urge the member toward 115 or away from the table 56, according as the spring is to the rear or to the front of the axis of pivot 62. The clamp may be operated by a finger-piece 68. While the ledger-sheet is held in position by rollers 41 and 42, the bill-sheet is held by the clamp, and the record-sheet 12, held on the platen by the tally-strip device, may be fed around 120 the platen, beneath the collating table 35, and to the rear thereof, and forming the lowermost sheet. In adjusting the sheets 125 130

10 and 11, the ledger-sheet 11 may be held in adjusted position by the collating-rolls 41 and 42, while the bill-sheet 10 is adjusted, or the bill-sheet 10 may be adjusted first and 5 may then be held in adjusted position by the sheet-gripping clamp 61, while the ledger-sheet 11 is adjusted or collated by means of the collating-rolls 41 and 42. The collating-rolls 41 and 42 are particularly 10 adapted for use in adjusting a work-sheet which is overlaid in the machine by another work-sheet, in which case the overlying work-sheet prevents free access to the underlying sheet which is to be adjusted, such, for 15 example, as the ledger-sheet 11 which is overlaid by the bill-sheet 10. Also the collating-rolls 41 and 42 enable convenient adjustment of a work-sheet should ready access to the sheet at the front of the 20 machine be interfered with by parts of the machine, such, for example, as the auxiliary collating-table 36, behind which the ledger-sheet 11 passes. When all the sheets have 25 been adjusted the pressure-rolls 32 and 33 are then thrown on, and ledger, bill, and record-sheets typed simultaneously. An additional wing-scale 70 is provided, mounted in the usual manner, and designed to aid in adjusting the sheets easily when the carriage 30 is at one end of its travel. The tally-strip mechanism may be of the same general form as described in the patent to Hart, No. 1,281,160, dated October 8, 1918.

In order to facilitate line-feeding of the 35 bill-sheet 10 and the ledger-sheet 11 during the typing operation, the clamp 61 and the collating-rolls 41 and 42 may be released. Also the clamp and the collating-rolls should be released when a bill has been typed and 40 the ledger and bill-sheets are to be withdrawn from the machine. It is desirable to provide mechanism for simultaneously releasing the clamp holding the bill-sheet and separating the auxiliary rolls 41 and 42 45 holding the ledger-sheet. This means comprises a finger 71, fixed to shaft 44 and projecting upwardly until it is capable of resting just at the front of the table section 56, upon which the bill-sheet is held, as shown 50 in broken lines in Figure 4. Member 61 of the clamp is provided with an extension 72, beneath which finger 71 is adapted to lie when the clamp and the collating-auxiliary rolls are in effective position. It will be 55 apparent that upon actuation of finger-piece 52, shaft 44 will be rocked rearwardly, carrying with it finger 71, which will rotate member 61 to ineffective position. The pressure-rolls 32 and 33 having been cast off 60 in the usual manner, the bill-sheet and ledger-sheet may be freely withdrawn together.

A paper-finger 75 is supported on a pivot 76 on the front rail of the carriage, and held 65 in effective or ineffective position by a leaf

spring 77 engaging a block 78 on which the finger is fixed, and is adapted to direct the sheets against the front of the auxiliary collating table at a point intermediate the side edges of the sheets.

In the machine of the present invention, if for any reason it should be found desirable to type another work-sheet in addition to the bill-sheet 10, ledger-sheet 11 and tally-strip 12, or corresponding sheets, such additional sheet may be inserted as an outer sheet and may be gaged and adjusted over the auxiliary front collating table 56 while the other sheets in the machine are held in position by the means hereinbefore described. However, in view of the particular construction of the clamp-releasing means shown in the drawings, such additional sheet should be sufficiently narrow to escape the clamp-releasing finger 71 at the 85 left margin of the sheet. Of course, if desired, a plurality of work-sheets may be superimposed and all adjusted together, and may be all held in adjusted position by the clamp 61.

Variations may be resorted to within the scope of the invention, and portions of the improvements may be used without others.

Having thus described my invention, I claim:

1. In a front-strike typewriting machine, the combination with a platen-frame and a revoluble platen journaled therein, of a rear paper-table fixed in said frame and provided with side-edge gages for aligning thereon a wide work-sheet, and provided with other side-edge gages for separately aligning thereon a narrow work-sheet lying between the edges of the wide work-sheet, devices carried by the platen-frame at the front of the platen for separately aligning each of said sheets to conform to its rear alignment, said devices comprising a wide front collating table provided with side-edge gages for aligning the wide work-sheet, and a narrow front collating table provided with side-edge gages for separately aligning the narrow work-sheet, and releasable means for gripping the narrow sheet to the narrow collating table independently of the wide sheet, and in any position to which the narrow sheet may be collated.

2. In a front-strike typewriting machine, the combination with a platen-frame and a revoluble platen journaled therein, of a rear paper-table fixed in said frame and provided with side-edge gages for aligning thereon a wide work-sheet, and provided with other side-edge gages for separately aligning thereon a narrow work-sheet lying between the edges of the wide work-sheet, devices carried by the platen-frame at the front of the platen for separately aligning each of said sheets to conform to its rear alignment, said devices comprising a wide

- 4
- front collating table provided with side-edge gages for aligning the wide work-sheet, and a narrow front collating table provided with side-edge gages for separately aligning 70
 5 the narrow work-sheet, and releasable means extending over the narrow collating table from one side thereof for gripping the narrow sheet to said narrow table independently of the wide sheet, to retain said narrow sheet 75
 10 in adjusted position while the wide sheet is being adjusted.
3. In a front-strike typewriting machine, the combination with a platen-frame and a revoluble platen journaled therein, of a rear 80
 15 paper-table fixed in the platen-frame and provided with side-edge gages for aligning a wide work-sheet, said rear paper-table having a chute formed therein providing side-edge gages for aligning a narrow work- 85
 20 sheet lying between the edges of the wide work-sheet and overlying the latter upon the platen, devices carried by the platen-frame at the front of the platen for separately aligning each of said sheets to conform to its rear alignment, said devices comprising a wide collating table provided with side-edge gages for aligning the wide work-sheet, and a narrow collating table in spaced relation at the front of the wide collating 90
 25 table and provided with side-edge gages for aligning the narrow work-sheet; a releasable sheet-gripping clamp associated with the narrow collating table for holding the narrow sheet in adjusted position, collating 95
 30 means for adjusting the wide work-sheet comprising front and rear sheet-gripping collating rolls associated with the wide collating table, and means for rotating said collating rolls in either direction to any desired extent for correspondingly adjusting the wide work-sheet to any desired position relatively to the printing line on the platen, whereby each of said work-sheets may be held in position to enable the other 100
 35 sheet to be adjusted.
4. In a front-strike typewriting machine, the combination with a platen-frame and a revoluble platen journaled therein, of a rear paper-table fixed in the platen-frame and 105
 50 provided with side-edge gages for aligning a wide work-sheet, said rear paper-table having a chute formed therein providing side-edge gages for aligning a narrow work-sheet lying between the edges of the wide work-sheet and overlying the latter upon the platen, devices carried by the platen-frame at the front of the platen for separately aligning each of said sheets to conform to its rear alignment, said devices comprising a wide collating table provided with side-edge gages for aligning the wide work-sheet, and a narrow collating table in spaced relation at the front of the wide collating 110
 55 table and provided with side-edge gages for aligning the narrow work-sheet; a releasable sheet-gripping clamp associated with the narrow collating table for holding the narrow sheet in adjusted position, collating means for adjusting the wide work-sheet comprising front and rear sheet-gripping collating rolls associated with the wide collating table, and means for rotating said collating rolls in either direction to any desired extent for correspondingly adjusting the wide work-sheet to any desired position relatively to the printing line on the platen, whereby each of said work-sheets may be held in position to enable the other sheet to be adjusted.
5. In a typewriting machine, the combination with a revoluble platen, of releasable sheet-gripping means independent of the platen for holding a work-sheet in adjusted position on the platen, releasable collating rolls independent of the platen for gripping another work-sheet passing around the platen, and means for rotating said rolls in either direction to any desired extent for adjusting the work-sheet gripped thereby to any desired position relatively to the printing line on the platen. 125
 6. In a typewriting machine, the combination with a revoluble platen, of means for holding an inner work-sheet in position on the platen, releasable sheet-gripping means independent of the platen for holding an outer work-sheet in adjusted position on the platen, and collating means for adjusting an intermediate work-sheet relatively to the printing line on the platen without disturbing said inner and outer work-sheets, comprising co-operating collating rolls to grip the intermediate sheet independently of the platen, means for rotating said rolls in either direction to any desired extent for correspondingly adjusting the intermediate work-sheet to any desired position relatively to the printing line on the platen, and means for separating the collating rolls to release the adjusted intermediate work-sheet. 130
 7. In a front-strike typewriting machine, the combination with a revoluble platen, of a collating table at the delivery side of the platen, front and rear collating rolls associated with the collating table to grip a work-sheet passing around the platen and over said collating table, means for rotating said rolls in either direction to any desired extent for correspondingly adjusting the work-sheet to any desired position relatively to the printing line on the platen, a second collating table spaced forwardly from the first at the delivery side of the platen for a second work-sheet passing 135

- around the platen at the outside of said first work-sheet, a releasable sheet-gripping clamp associated with said second collating table for holding said second work-sheet in adjusted position so as to enable the first work-sheet to be adjusted relatively thereto by means of said collating rolls, and means for separating the collating rolls to release the adjusted work-sheet held thereby.
8. In a front-strike typewriting machine, the combination with a revolute platen, of a collating table at the delivery side of the platen, front and rear collating rolls associated with the collating table to grip a work-sheet passing around the platen and over said collating table, means for rotating said rolls in either direction to any desired extent for correspondingly adjusting the work-sheet to any desired position relatively to the printing line on the platen, a second collating table spaced forwardly from the first at the delivery side of the platen for a second work-sheet passing around the platen at the outside of said first work-sheet, a releasable sheet-gripping clamp associated with said second collating table for holding said second work-sheet in adjusted position so as to enable the first work-sheet to be adjusted relatively thereto by means of said collating rolls, means for concomitantly releasing the grip of said collating rolls and of said clamp to enable the adjusted work-sheets to be line-fed, and means for line-feeding the adjusted work-sheets.
9. In a typewriting machine, the combination with a platen and a platen-frame, of a rear paper-table fixed in said frame, devices associated with the rear paper-table for separately supporting and aligning superposed work-sheets, a collating device at the front of the platen comprising superposed and spaced tables rigidly connected one to the other and forming upper and lower guiding and supporting tables for separately supporting and aligning said sheets to conform to their rear alignment, rear feed-rolls projecting through the lower of said front paper-tables, front feed-rolls co-operating therewith to hold a sheet in position on said lower table, and a clamp on said upper table to hold a second sheet in position thereon.
10. In a typewriting machine, the combination with a platen and a platen-frame, of a rear paper-table fixed in said frame, devices associated with the rear paper-table for separately supporting and aligning superposed work-sheets, a collating device at the front of the platen comprising superposed and spaced tables rigidly connected one to the other and forming upper and lower guiding and supporting tables for separately supporting and aligning said sheets to conform to their rear alignment, rear feed-rolls projecting through the lower of said front paper-tables, front feed-rolls co-operating therewith to hold a sheet in position on said lower table, and a clamp on said upper table to hold a second sheet in position thereon.
11. In a typewriting machine, the combination with a platen and a platen-frame, of a rear paper-table fixed in said frame, devices associated with the rear paper-table for separately supporting and aligning superposed work-sheets, a collating device at the front of the platen comprising superposed and spaced tables rigidly connected one to the other and forming upper and lower guiding and supporting tables for separately supporting and aligning said sheets to conform to their rear alignment, rear feed-rolls projecting through the lower of said front paper-tables, front feed-rolls co-operating therewith to hold a sheet in position on said lower table, and a clamp on said upper table to hold a second sheet in position thereon.
12. In a front-strike typewriting machine, the combination with a revolute platen, of a plurality of collating tables at the front of the platen, separate sheet-gripping means for separately and independently gripping work-sheets on the different collating tables independently of the platen, and means for concomitantly releasing all of said sheet-gripping means.
13. In a front-strike typewriting machine, the combination with a revolute platen, of spaced superposed collating tables at the front of the platen, a releasable sheet-gripping device associated with each collating table for separately gripping and holding superposed work-sheets in adjusted position on the platen, and means for concomitantly releasing both of said sheet-gripping devices.
14. In a typewriting machine, the combination with a revolute platen, of a releasable sheet-gripping device independent of the platen for holding a work-sheet in ad-

justed position on the platen, releasable collating rolls independent of the platen for gripping another work-sheet passing around the platen, means for rotating said rolls in either direction to any desired extent for adjusting the work-sheet gripped thereby to any desired position relatively to the printing line on the platen, and means for comitantly releasing said collating rolls and 10 said sheet-gripping device.

15. In a front-strike typewriting machine, the combination with a revoluble platen, of a releasable sheet-gripping device independent of the platen for holding a work-sheet 15 in adjusted position on the platen, and collating means at the front of the platen for adjusting an underlying work-sheet relatively to the printing line on the platen without disturbing the overlying work-sheet 20 held by said sheet-gripping device, said collating means comprising releasable co-operating collating rolls to grip the underlying sheet independently of the platen, and means for rotating said rolls in either direction to 25 any desired extent for adjusting the underlying work-sheet gripped thereby to any desired position relatively to the printing line on the platen.

16. In a typewriting machine, the combination with a revoluble platen, of releasable 30 sheet-gripping means independent of the platen for holding a work-sheet in adjusted position on the platen, releasable collating rolls independent of the platen for gripping another work-sheet passing around the 35 platen, and collating-roll-rotating means for adjusting the work-sheet gripped by the rolls.

17. In a front-strike typewriting machine, the combination with a revoluble platen, of 40 a plurality of collating tables at the front of the platen, one table in front of the other, so that the rear work-sheet occupies a position between the tables, and separate sheet-gripping means for separately and independently 45 gripping work-sheets on the different collating tables independently of the platen, in any positions to which said sheets may be collated, each of said tables open at the top affording unobstructed passage for the 50 sheets.
